UNITED STATES PATENT OFFICE.

AUGUSTUS H. WOODRUFF, OF IRVINGTON, NEW JERSEY, ASSIGNOR OF
ONE-HALF TO FRANK F. SMITH, OF NEWARK, NEW JERSEY.

LOCK AND GRAVITY-BOLT FOR WINDOWS.

No. 815,669.

Specification of Letters Patent.

Patented March 20, 1906.

Original application filed May 12, 1905, Serial No. 260,149. Divided and this application filed September 7, 1905. Serial No. 277,801.

To all whom it may concern:

Be it known that I, AUGUSTUS H. WOODRUFF, a citizen of the United States, residing at Irvington, in the county of Essex and State of New Jersey, have invented certain new and useful Improvements in Locks and Gravity-Bolts for Windows; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

My present invention relates generally to improvements in locks and gravity-bolts for use with windows, skylights, and the like, and is in the nature of a division of my former application for Letters Patent, filed May 12, 1905, Serial No. 260,149.

The invention relates more particularly to a novel form of lock including a gravity-bolt, with means for pushing the same back and at the same time for opening the window.

The invention therefore has for its principal object to provide a simply-constructed and efficiently - operating lock and gravity-bolt, all arranged for holding a window or the like in its closed position, but which is provided with means for pushing the bolt back for opening the window or the like, all with a view of providing a device which can be readily manipulated and with a view of dispensing with the use of springs, which are apt to become weak and useless.

A further object of this invention is to provide a bolt working from the top and inside of the frame, so as not to become clogged with dirt or by paint sticking the bolt fast, and, furthermore, to provide a novel and simple means for effectively opening and closing a fixture, as a window, skylight, door, and the like, which when closed is positively held in its closed position by means of the gravity-bolt.

With the various objects of my present invention in view the same consists in the novel construction of lock and gravity-bolt for a fixture—such as a window, skylight, door, shutter, and the like—with means for pushing the bolt back for opening the window and the like; and, furthermore, this invention consists in the various arrangements

and combinations of devices and parts, as well as in the details of the construction of the same, all of which will be hereinafter more fully described and then finally embodied in the clauses of the claim, which are appended to and which form an essential part of this specification.

The invention is clearly illustrated in the accompanying drawings, in which—

Figure 1 is a transverse vertical section of a metallic or other suitable window-frame and window and of the said lock and gravity-bolt and means for pushing back the same, showing the window held open; and Fig. 2 is a similar sectional representation of the same parts, but showing the window held in its locked or closed position by the gravity-bolt in the upper part of the window-frame. Fig. 3 is a vertical section, on an enlarged scale, of the upper portion of the window-frame and window-sash, showing the gravity-bolt in its locked engagement, with the parts in the lock - casing being shown in elevation, while other parts in said lock-casing are represented in section. Fig. 4 is a top view of the gravity-bolt and guide-plate in which it is movably arranged. Fig. 5 is a detail vertical section of the lock-casing and part of a window - frame, said section being taken on line 5 5 in said Fig. 3 looking in the direction of the arrow X, the latch of the locking mechanism, however, being shown in its raised position. Fig. 6 is a sectional representation of a lock-casing provided with a lock mechanism of a slightly-modified form of construction, but still embodying the principles of the present invention.

Similar characters of reference are employed in all of the said above-described views to indicate corresponding parts.

Referring now to the several figures of the drawings, the reference character 1 indicates a metallic or other suitable window-frame of any usual construction, which is provided with a suitably - formed hollow portion 2, forming a chamber, substantially as shown in Figs. 1 and 2 of the drawings. In the lower wall or base 3 of this portion 2 is a suitable hole or opening 4 for the purposes to be presently set forth. The sheet metal from which the frame 1 is made is also provided at the back at a point below said portion 2 with a suitably-formed and laterally-extending angular shield or rain-drip 5.

One or more window-sashes 6, preferably made of sheet metal, are pivotally suspended or swung in the opening of the window-frame, each sash having an upper hollow portion 7 and a lower hollow portion 8, respectively provided with the channel-shaped receiving edges 9 for securing the usual window-glass 10 between said upper portion 8 and lower portion 9. Suitable stops 11 may also be provided at the back on opposite sides of the opening in the window-frame 1, against which the window-sash is swung when opened to limit the pivotal movement of the window, as clearly shown in Figs. 1, 2, and 3 of the drawings.

Suitably secured in the upper hollow portion 7 of the window-sash during the process of bending the sheet metal into shape is a lock-casing and its mechanism contained therein, as clearly indicated in the several figures of the drawings. This casing usually consists of two sections 12 and 13, as indicated in Fig. 5 of the drawings, each section being provided with a perforated flange 14, screw-bolts 15 and nuts 16 being employed for securing the sections of the lock-casing against the inner face of one of the sides of the portion 7, substantially as shown in Figs. 3 and 5 of the drawings. One of said sections, as 12, is provided with screw-receiving holes 17, while the other section 13 is formed with interior posts 18, provided with screw-threaded sockets 19, placed directly opposite the screw-holes 17 for the reception of screws 20, by means of which the two sections 12 and 13 are secured together, as shown. A cover or plate 21, provided with a holding-flange or lugs 22, is arranged over the upper open portion of the two connected sections 12 and 13, the said cover or plate 21 being held in place by said flange or lugs 22 and by the inner face of the upper wall of said portion 7. The said cover or plate 21 is provided with an opening 23, and in said upper wall of the portion 7 is a correspondingly-formed opening 24, which registers with the said opening 23, and thereby forms one continuous opening through said upper wall of the portion 7 and said cover or plate 21. Pivotally arranged upon the upper post 18 of the said section 13 is a latch 25, having a recess 26 in its pivoted portion and provided with a lifting end or portion 27. Normally the said latch 25 is in the position indicated in Figs. 2 and 3 of the drawings; but when the window is opened said latch is actuated in the manner to be hereinafter more fully described, whereby its lifting end or portion 27 is moved into the opening formed by the openings 23 and 24, previously mentioned, as clearly indicated in dotted outline in said Fig. 3 and in section in Fig. 5.

Suitably secured upon the inner face of the base of the hollow portion 2 of the frame 1 is a plate 28, provided with an upwardly-ex-

tending guiding-socket 29. This socket is preferably of an angular configuration in cross-section, as indicated in the dotted outline in said Fig. 6, which is preferably wider at the top than at the bottom and has a pin 70 30 extending across its guiding-opening. Movably arranged within the said guiding-socket is a bolt 31, having an elongated opening 32, through which the said pin 30 extends and upon which the said bolt is movably arranged. The lower holding portion of said bolt has a rounded edge 33, and upon its upper end it may be provided with a head or enlargement 34, which normally rests upon the upper marginal edge of the said guiding-socket 29 and by gravity forces the lower holding portion of the bolt 31 into and through the previously-mentioned openings 23 and 24 to retain the window-sash in its closed relation in the window-frame in the 80 manner clearly indicated in Figs. 2 and 3 of the drawings.

Referring now more particularly to Fig. 3 of the drawings, it will be seen that in the front and rear walls of the said upper hollow portion 90 7 of the window-sash I have placed suitably-disposed and upwardly-inclining openings 35 and 36, respectively, the two sections 12 and 13 being respectively provided with semicircular or other suitably-shaped guide portions 95 37 and 38, in which is movably arranged an upwardly-extending and angularly-inclining tube 39, provided with a teat or projection 40, which extends in operative engagement into the recess 26 of the latch 25. Within the said tube 39 is a rod 41, having an upper shouldered portion 42, which has a screw-threaded part 43 for the screwing thereon of a nut 44. The lower end portion of the said rod 41 extends from the opening 35 in the front piece of the portion 7 of the window-sash and is provided with a receiving eye or loop 45. From an inspection of the drawings it will be seen that the said nut 44 rests upon the upper edge of the tube 39 to prevent the displacement of the said rod 41 from said tube 39. It will also be noticed that the weight of the pivoted latch 25 under normal conditions (indicated in Fig. 3 of the drawings) retains the tube 39 and parts connected therewith in the raised position shown in said figure.

Suitably connected with the receiving eye or loop 45 of the said rod 41 is a flexible connection 46, such as a rope or chain, by means of which the tube 39 is actuated to operate the latch 25 and lifts the gravity-bolt 31 from its holding engagement with the window-sash in the manner to be presently described.

The operation of the device will be clearly understood from an inspection of Figs. 1, 2, and 3 of the drawings and need not be more particularly described. Suffice it to say that when a pull is exerted upon the flexible connection 46 the tube 39 and rod 41 receive a 130

slight movement in an angularly-downward direction, causing the projection 40 to swing the latch 25 upwardly and against the rounded end of the bolt 31. The said lower end 5 portion of the bolt 31 is thus pushed upwardly from its holding engagement with the openings 23 and 24, and the window-sash is swung into its opened relation, in which it is held by the fastening of the flexible connection 46 to a hook or other object in any usual manner. When the flexible connection is again released, the sash and its window at once return to the closed position in the frame 1, as clearly indicated in Fig. 2, the 15 gravity-bolt 31 being first raised by contact with the upper portion of the sash 6. The bolt immediately drops back into the holes or openings 24 and 23, and thereby positively retains the closed window in its locked relation in the frame 1. It will also be seen that the said shield or rain-drip 5 protects the nut 44 and tube 39 against corrosion by preventing the rain from beating upon the nut and dripping down into the said tube 39.

25 In Fig. 6 of the drawings I have shown a slightly-modified arrangement and construction of lock mechanism. In this construction, in which the general construction of the parts is practically the same as that hereinabove described, the tube 39 is movably arranged upon a long support 47, which extends from the opening 35 to the opening 38 in the opposite sides of the casing. The latch 25 in this construction is also of a slightly-different configuration, the same being provided with a long curved edge 48, upon which the holding end of the bolt 31 rides, as indicated in the dotted outline in said Fig. 6 of the drawings, and is raised and lowered in a 35 manner similar to that previously described.

I claim—

1. The combination, with a metallic or other suitable frame having a hollow portion, and a fixture, as a window, door, or the like, pivotally swung in said frame, said fixture also having a hollow part, of a gravity-bolt in the hollow portion of the frame, and mechanism in the hollow part of the fixture for lifting said gravity-bolt, consisting of a 45 pivoted latch, and a tube provided with a projection in engagement with a part of said latch, a rod in said tube having a nut at one end, and a flexible connection at the other end of said rod, substantially as and for the 50 purposes set forth.

2. The combination, with a metallic or other suitable frame and fixture, as a window, door, or the like, pivotally connected with said frame, of means for holding said fixture in an open position, in said frame, comprising a rod extending through said frame, a nut upon the free end of said rod, and a rain-shield upon said frame beneath which said nut is located, substantially as and for 60 the purposes set forth.

3. The combination, with a hollow metallic or other suitable frame and a fixture, as a window, door, or the like, pivotally connected with said frame, said fixture having a hollow part, provided with guiding portions, of a 70 tube movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture, substantially as and for the purposes 75 set forth.

4. The combination, with a metallic or 80 other suitable frame and fixture, as a window, door, or the like, pivotally connected with said frame, of means for opening said fixture, comprising a rod extending through said frame, and a nut upon the one free end 85 of said rod in engagement with one side of said fixture, and a pull device connected with the opposite end of said bolt, substantially as and for the purposes set forth.

5. The combination, with a hollow metallic or other suitable frame and a fixture, as a window, door, or the like, pivotally connected with said frame, said fixture having a hollow part, provided with guiding portions, of a tube 90 movably arranged in said guiding portions, a latch in said hollow part, means connected with said tube for actuating said latch, a gravity-bolt in said hollow frame, and means connected with said tube for actuating said latch and raising the said bolt from holding 95 engagement with the pivoted fixture, substantially as and for the purposes set forth.

6. The combination, with a hollow metallic or other suitable frame and a fixture, as a window, door, or the like, pivotally connected 100 with said frame, said fixture having a hollow part, provided with guiding portions, of a tube 105 movably arranged in said guiding portions, a latch in said hollow part, means connected with said tube for actuating said latch, a gravity-bolt in said hollow frame, and means connected with said tube for actuating said latch and raising the said bolt from holding engagement with the pivoted fixture and holding 110 said fixture in an open position in said frame, comprising a rod extending through said tube, and a nut upon the free end of said rod, substantially as and for the purposes set forth.

7. The combination, with a hollow metallic or other suitable frame and a fixture, as a window, door, or the like, pivotally connected with said frame, said fixture having a hollow part, provided with guiding portions, of an actuating means movably arranged in said 120 guiding portions, a holding means in the hollow part of the frame having a portion normally in holding engagement with the said pivoted fixture, and a pivoted latch adapted 125 to be operated by the movement of said ac- 130

tuating means for releasing said holding means from its engagement with said pivoted fixture, substantially as and for the purposes set forth.

- 5 8. The combination, with a hollow metallic or other suitable frame and a fixture, as a window, door, or the like, pivotally connected with said frame, said fixture being provided with a hollow part provided with a vertical 10 guide 29, and a gravity-bolt movable vertically in said guide, said bolt having a portion normally in holding engagement with said pivoted fixture, means connected with said guide and bolt for limiting the movement of said hollow part of said fixture, and means adapted to be operated by the movement of said actuating means for releasing said bolt from its engagement with said pivoted fixture, substantially as and for the purposes set forth.
- 15 9. The combination, with a hollow metallic or other suitable frame and a fixture, as a window, door, or the like, pivotally connected with said frame, said fixture being provided with a hollow part provided with a vertical 20 guide 29, and a gravity-bolt movable vertically in said guide, said bolt having a portion
- 25

normally in holding engagement with said pivoted fixture, means connected with said bolt, an actuating means movably arranged in the hollow part of said fixture, and a pivoted latch adapted to be operated by the movement of said actuating means for releasing said holding means from its engagement with said pivoted fixture, substantially 30 as and for the purposes set forth.

10. The combination, with a frame and a fixture, as a window, door, or the like, pivotally connected with said frame, said frame having a bolt-receiving portion, and said frame having a rod-receiving portion, a bolt in said bolt-receiving portion, a rod movably arranged in said rod-receiving portion, and means connected with said rod for actuating said bolt, substantially as and for the purposes set forth.

In testimony that I claim the invention set forth above I have hereunto set my hand this 24th day of July, 1905.

AUGUSTUS H. WOODRUFF.
